CLAIM

The ornamental design for a flow cell device, as shown and described.

DESCRIPTION

FIG. 1 is a top plan view of the flow cell device comprising our new design;

FIG. 2 is a bottom plan of the design of FIG. 1;

FIG. 3 is a left side elevational view of the design of FIG. 1;

FIG. 4 is a right side elevational view of the design of FIG. 1;

FIG. 5 is a front elevational view of the design of FIG. 1;

FIG. 6 is an enlarged rear elevational view of the design of FIG. 1;

FIG. 7 is a right-rear perspective view of the design of FIG. 1; and,

FIG. 8 is a left-rear perspective view of the design of FIG. 1.

The broken lines shown in the drawings illustrate portions of the flow cell device that form no part of the claimed design. The dash-dot-dot broken lines depict the boundaries of the claim and form no part thereof.
